CHECK CONTROLLED APPARATUS

Clarence F. Cookson, Rutherford, N. J.

Application December 1, 1939, Serial No. 307,096

8 Claims. (Cl. 194—1)

My present invention relates to check controlled apparatus, for example, in toy banks, and more particularly to such as are provided with means for recording the denomination of a coin deposited in the apparatus, though its use is by no means so limited, since, in its broader aspect, it is useful in many locations in which it is desired to control a mechanism by means of checks of different sizes.

Among the objects of this invention are to provide an apparatus which will receive coins or checks of different denominations and record, upon a suitable paper or other sheet or strip material, the amount of each coin deposited; to provide an improved mechanism for automatically recording the denominations of coins deposited in the apparatus; to provide a mechanism which will automatically prevent the depositing of a coin unless the mechanism is in a condition to receive and hold the coin until it has been recorded; to provide a mechanism of the character indicated which will automatically release a coin when it has been recorded and the actuating means has been released; to provide a mechanism of the character indicated which will insure that no single coin will be recorded more than once for a single insertion into the apparatus; to provide an apparatus of the nature indicated which will respond in different desired ways to the insertion of different sized checks; and such further objects, advantages, and capabilities as will hereafter appear and as are inherent in the structure disclosed herein. My invention further resides in the combination, construction, and arrangement of parts illustrated in the accompanying drawings, and, while I have shown therein what is now regarded as the preferred embodiment of this invention, I desire the same to be understood as illustrative only and not to be interpreted in a limiting sense.

In the drawings annexed hereto and forming a part hereof,

Figure 1 represents an elevation of my invention with the position of the casing for enclosing the operative mechanism shown in dotted lines;

Figure 2 represents an elevation at a right angle to Figure 1 and looking at the left hand side of that figure;

Figure 3 is a fragmentary view corresponding to Figure 1 but with the operative mechanism in a different position;

Figure 4 represents a side elevation corre-

sponding to Figure 2 but with the parts in the positions represented by Figure 3;

Figure 5 represents an elevation corresponding to Figures 1 and 3 but with the operative parts in a position intermediate between the positions shown in these figures;

Figure 6 represents a side elevation of the structure shown in Figure 5 but with the enclosing casing shown in position around the operative mechanism;

Figure 7 represents a fragmentary elevation corresponding to Figures 1, 3, and 5, but with the operative parts in a still different position of adjustment;

Figure 8 represents a horizontal section of the operative mechanism taken just above the operating lever, as indicated by the line 8—8 of Fig. 7, with the parts in the position shown in that figure;

Figure 9 represents a fragmentary elevation of the structure as shown in Figure 1 but looking in the opposite direction; and

Figure 10 represents a vertical section approximately along the plane indicated by the line 10—10, Fig. 1 through the structure as shown in Figure 1, just at the left of the coin chute.

Reference will now be made in greater detail to the annexed drawings for a more complete description of this invention. A coin box 1 serves

as a base for supporting the operative mechanism which is enclosed within a casing 2. A wall or bracket 3 has an upright edge flange 4 from which a flange 5 extends inwardly parallel to the wall 3. A pivot member 6 extends through the

parts 3 and 5 and pivotally supports the lever 7 which is actuated upwardly by the spring 8, coiled about the pivot member 6, and has one end resting against the flange 4 and the other end hooked under the lever 7. The tendency of this spring 8 is, therefore, to hold the lever up in the position shown in Figure 1. A slide 9 has a plurality of arms 10 extending rearwardly therefrom through slots 11 in the wall or bracket 3. The ends 10a of these arms 10 are bent laterally to serve as securing means to hold the slide to the wall, in slidable relation.

An inclined wall 12 extends upwardly from the upper edge of the wall 3 and has a pair of flanges 13 extending forwardly therefrom to form part of the upper section of a coin chute, the fourth wall of which is shown at 14. The wall 14 has a pair of flanges 15 located between the side flanges 13. A pair of fingers 16 extend rearwardly through the wall 12 and are bent outwardly so that they hold the wall 14 of the chute

in assembled relation with the remainder of the upper section thereof. These fingers 16 are loosely mounted in holes in the wall 12 so as to permit the wall 14 to have pivotal motion with respect to the rest of the chute. A flange 17 projects rearwardly from the wall 14 and is apertured, as indicated at 18 in Figure 3, to permit coins to be inserted therethrough. Between the slot 18 and the rear edge of the flange 17 is a strip which is wide enough to cover a slot 18a through the top of the casing 2; so that coins cannot be inserted unless the wall 14 is tilted rearwardly so as to bring into alignment the slot 18 and the corresponding slot 18a in the top of the casing. An arm 19 extends forwardly from the flange 17 at one side thereof and, as shown in Figure 1, is engaged by the lever 7 when in its uppermost position. When in this position, the wall 14 is turned about its pivots to bring the slots into registry. Therefore, when the lever 7 is in its uppermost position, a coin may be inserted through the cooperating slots and will drop down through the coin chute.

A lever section 20 of the coin chute is fixedly mounted on the slide 9 by having lugs 20a, which extend through openings in the slide 9, bent over to secure the coin chute to slide. It will therefore be seen that, if the slide 9 is caused to move downwardly, the lower section 20 of the coin chute will also be moved in that direction. A spring 21, back of the wall 3, has its upper end secured to an apertured ear 21a projecting rearwardly from the wall and its lower end connected to an apertured ear 21b projecting rearwardly from the lower portion of the slide 9. Therefore, when the slide is moved downwardly and then released, the spring 21 tends to return it to its upper position, with the arms 10 engaging the upper ends of the slots 11.

A lever 22 is pivoted at 23 to the upper portion of the lower section of the coin chute and may swing laterally in a plane parallel to the chute. Adjacent its lower end, this lever 22 is provided with a pair of fingers 24 extending rearwardly through a cut-out portion of the chute section 20. The cut-out portion of the chute is designated in Figures 1, 5, and 9 by the numeral 25. An arm 26 (see Figures 7 and 8) extends forwardly from the slide 9 and a corresponding arm 27 from the lever 22, and these arms are connected by a spring 28 which tends to swing the lever 22 toward the right, as viewed in Figure 1. This holds the fingers 24 in the path of a coin passing downwardly through the chute 20 unless the lever 22 is swung to the left to remove the fingers from the path of the coin. This is done by means of a hooked arm 30, pivotally mounted on the pivot member 31.

The pivot member 31 extends through opposite sides of a channel-shaped member 32 pivotally carried by the pivot pin 33 mounted in the slide 9. An arm 34 extends outwardly from the bent portion of the member 32, for the attachment of a link 35 which is connected at one end, by a pivot member 37, with the lever 7. It will therefore be clear that, when the lever 7 turns about the pivot 6, motion will be transmitted through the link 35 and, from this, to the arm 34 and member 32. When the member 32 is free to swing about its pivot 33, it will do so and it may pass through any position between that shown in Figure 1 and that shown in Figure 7. At its end remote from the pivot 33, the member 32 is provided with a flange 38 around

which extends a type band 39 carrying printing type 40. As the member 32 swings, the type contacts an inking roller 41 carried by a bracket 42 upon the top of the box 1. The inking roller 41 is connected to the bracket 42 by a pivot member 43 so that it may rotate as the printing type engages and swings past it upon movement of member 32. Paper, such as a bank book, may be inserted under the fingers 44 which tend to hold the paper in place and also to prevent printing on the paper of anything but the proper denomination to indicate the value of the coin dropped into the chute. Abutments 46 extend upwardly from the top of the coin box 1 to serve as guides for positioning the paper which is inserted under the fingers 44.

In the rearward arm 32b of member 32 are formed notches 48 and 49 which divide it into three fingers 32c, 32d, and 32e. These enter the coin chute 20 between the fingers 24 and 50 and above the latter to serve to limit the amount which the member 32 may swing about its pivot 33. The finger 50 is formed along the edge of the coin chute 20 and extends backwardly to the back wall 9 thereof. This finger 50 cooperates with the upper finger 24 in preventing coins from dropping out of the edge of the chute 20 prior to engagement of the fingers 32c, 32d, and 32e with the edges of coins dropped into the chute. This determines which one of the printing type faces is to engage the paper to do the printing. In Figures 1, 3, and 7, coins of different sizes are represented, and Figures 3 and 7 illustrate how the fingers 32c, 32d, and 32e engage the coins to limit the swinging of the member 32. The bridge 32a connecting the two arms of the member 32 is contacted by an arm 51 forming a part of the hooked member 30 and limits the pivotal motion thereof in one direction. Pivotal motion in this direction is caused by the spring 52 which is coiled about the pivot member 31. It should be understood that as the fingers 32c, 32d, 32e reach into the chute 20, they alternate with the arms 24 and 50, extending into the chute different distances, and that the lowest finger, 32c, enters above the lower arm 24, the middle finger, 32d, entering between the two arms 24, and the upper finger 32e, entering between upper arm 24 and arm 50.

Let us assume that the operating lever 7 is in its uppermost position, as shown in Figure 1. When it is in this position, the opening 18a into the coin chute, through the top of the casing, is uncovered, the opening 18 through the flange 11 registering with 18a. Therefore, a coin may be inserted and, when dropped, it will fall until stopped by the fingers 24. If the coin is a 25-cent piece, it will come to rest almost entirely above the upper finger 24. If it is a 5-cent piece, it will, because of its smaller diameter, come to rest lower down and, if it is a 1-cent piece, it will almost pass this finger. If the coin is a 10-cent piece, it will pass the upper finger 24 and will come to rest against the lower finger 24. It is clear that when the swinging of member 32 is stopped by an end of one or another of its fingers striking a coin in the coin chute, further downward movement of the lever 7 will cause downward movement of member 32 by reason of the fact that the link 35 connects the lever 7 and member 32 and the latter is held against pivotal movement by the engagement of fingers 32c, 32d, or 32e with a coin. This brings a printing type face down into printing position, since the type will move in the same direction as the

slide 9. It is also clear that the distance which the member 32 swings is dependent upon the diameter of the coin which is in the chute.

From an inspection of the drawings, it is at once apparent that a coin cannot slide through the coin chute and escape into the coin box 1 until the fingers 24, carried by the lever 22, have been swung laterally out of the path of the coin. This is accomplished by the hook 54 engaging the flange 27 on member 22, as shown in Figure 5. However, this release does not take place until member 39 moves into the position shown in Figure 3, upon downward movement of the lever 1, and then starts to move toward the left upon upward movement of the lever 7, as illustrated in Figure 5.

A Y-shaped slot 55 is formed in the casing 2, as shown in Figure 6, one of the upper arms of this slot being designated 55a and the other 55b. When the lever 7 has been lowered to either of the positions illustrated in Figures 3 and 7 and is then released, it will go upwardly into the slot 55b, as shown in Figure 6. This will stop the upward movement of the lever 7 before the hook 54 releases the flange 27 of the lever 22. This gives the coin in the chute 20 time to drop into the coin box before the fingers 24, carried by the lever 22, can swing under the influence of the spring 28 into a position to catch the coin and prevent it from dropping. The slots 18 and 18a are out of registry and a coin can therefore not be inserted. When the lever 7 is moved by the operator downwardly and to the left from the position shown in Figure 6 and then permitted to rise to the upper end of the slot 55a, the member 39 is pulled farther to the left and released from the flange 27, thus permitting lever 22 to move to the right under the influence of spring 28. This brings the fingers 24 into the position shown in Figures 1, 2, and 3. Engagement of the angle of the lever 7 with the arm 19 causes the wall 14 to swing backwardly to the limit of its motion, as shown in Figure 2. In this position, the slots 18 and 18a are in alignment and a coin may be dropped through them into the coin chute, the operation being repeated as before.

In the operation of this device, it must first be seen that the lever 1 is at its upper limit, as shown in Fig. 1. This opens the upper end of the chute 20 so that a coin may be deposited therein. This coin then slides down until stopped by one of the arms 24, the point of stopping of the coin being dependent upon the size thereof, as explained above. The lever 7 is then pressed downwardly after the bank book or any suitable piece of paper has been inserted under the fingers 44. Fingers 32c, 32d, and 32e will be caused to engage the edge of the coin when 32a is swung downwardly about its pivot 33 by action of the lever 1, and the amount which 32a will be swung will be determined by the diameter and position of the coin. The fingers 32c, 32d, and 32e push the coin edgewise against the wall of the chute 20 opposite the opening into which the fingers extend. The fingers and the structure by which they are carried are then stopped and further movement of the lever 7 forces the printing head and its type band down into printing position. However, before this takes place, the hook 54 is raised up in front of the bracket 27 by the action of the spring 52. When printing has taken place, the lever 7 is released and it is turned upward about its pivot 6 by the spring 8. This swings the arm 30 about its pivot 33, causing the hook

54 to engage the bracket 27 and swing member 22 to the left, as viewed in Fig. 3. The lower end of this member 22 carries the arms 24 away from the coin chute 20. Since the coin is released from both the fingers and the arm, it drops freely to the coin-receptacle below. However, if member 22 is released too quickly, it will snap back under the influence of the spring 28 and sometimes catch the coin before it can leave the coin chute. In order to prevent this, the lever 7 is caught in its upward travel by the notch 55b before bracket 27 is released from hook 54. This position is shown in Fig. 5. If it is desired to deposit a coin, it is necessary to release the lever 7 from the notch 55b and let it go up into the notch 55a, in which position the angle of the lever will engage the plate 19, as shown in Figs. 1 and 9, and uncover the opening 18a, that is, it will place the openings 18 and 18a in alignment so that the coin can be dropped into the chute 20. When the lever 7 is released from the notch 55b and goes up into the notch 55a, the hook 54 pulls the bracket 27 toward the left, as viewed in Fig. 5, said bracket swinging about the pivot member 23. The hook 54 swings about the pivot 33 and the hook and bracket separate at a certain point slightly to the left of the position shown in Fig. 5. The separation is assisted by the slope of the under face of the bracket 27 in that position and 30 by the tension of the spring 28 which tends to push the arm 30 downwardly. The position of the bottom end of member 22 at its highest elevation is shown in Fig. 1, while its position at its lowest elevation is shown by dotted lines in Fig. 3 35 where its lower end is illustrated as being substantially in horizontal alignment with the bottom of the hook 30.

While I have disclosed this invention with particular regard to its use in connection with toy money banks, it is obvious that it may be used in various other constructions and, more especially, the check mechanism is capable of use independent of the printing mechanism for various purposes, such as in vending machines of certain types. It is capable of other uses also, and I therefore do not wish the annexed claims to be further limited than their language requires.

Having now described my invention, I claim:

1. A check controlled printing apparatus comprising a check chute, means to detain a check in said chute, pivoted means carrying a plurality of printing indicia, means to swing said pivoted means into edge engagement with a check detained in said chute, the position of said pivoted means being controlled by the diameter of the check, and means to reciprocate said pivoted means while in contact with said check into printing engagement with an article to be printed, the indicia printed being dependent upon the diameter of the check inserted in the mechanism.

2. In a mechanism of the character described, in combination, a support, printing means for printing denominations of checks put into the mechanism, a check chute supported by the support, a vertically movable slide supporting the printing means, operating mechanism connected to the printing means for swinging the printing means and causing it to move longitudinally to print the denominations of the checks put into the mechanism, said printing means being pivotally mounted on the slide, check-holding means pivotally connected with the check chute for holding checks in said chute, and releasing means connected with the printing means to cause the check-holding means to release the check after

1. In a printing operation has been completed, the swinging printing means being provided with check-engaging arms to engage the edge of a check in the check chute and limit swinging movement of said means in accordance with the diameter of the check inserted, whereby to assure the printing of the proper denomination to denote the value of the check inserted.

2. In a check controlled apparatus, a support, a gauging and operating assembly movably mounted on said support, said assembly including a check chute movable with said assembly, means for stopping checks of various sizes at different points along the length of said chute, means pivotally mounted on said assembly movable into engagement with a portion of the edge of a check in said chute, the portion of the edge of the check substantially diametric to said portion being in engagement with a wall of said chute, whereby lateral movement of the check in that direction is limited, means for reciprocating said assembly and said pivotally mounted means as a unit, means movable with said pivotally mounted means whereby the angular position during movement of said assembly is dependent upon the size of the check, and printing means carried by said pivotally mounted means and connected thereby to and movable with said chute into printing position, the position of the printing means when printing being dependent upon the amount of pivotal motion of the pivotally mounted means.

3. In a check controlled apparatus, a chute through which checks of various diameters may be passed, detaining means extending into the chute to stop checks of different diameters with their centers at different points longitudinally of the chute, gauging means movable in one direction to a position in which a portion thereof engages a check stopped by said detaining means, checks of different diameters stopping said gauging means in different positions and said gauging means and chute being movable in a different direction from the first mentioned direction with said gauging means held in stopped position as to its first mentioned motion by a check in the chute, and printing means having a plurality of printing positions, said printing means being movable jointly with said gauging means in both of its movements.

4. In a check controlled apparatus, a support, a controlling means comprising a check chute having an opening transversely of the thickness thereof and extending entirely to one edge thereof for the reception of check-engaging fingers, said check chute being connected to the support, fingers in said opening and extending transversely to the thickness of the chute to be engaged by checks passing through the chute whereby to stop different size checks at different points in the chute, said chute having an opening for receiving checks to be passed through the chute, supporting means for said fingers pivotally mounted on the chute to carry the fingers out of the opening, swingable actuating means pivotally mounted on the support, means on said actuating means swingable into the chute to engage an edge portion of a check therein and be stopped in different positions dependent upon the diameters of the checks, means connected with the actuating means, engaging the supporting means, and swinging the fingers out of the opening for releasing the checks from the fingers, and pivoted means for actuating the swingable means into check-engaging position, the fingers stopping and

holding inserted checks in different positions whereby to stop said swingable means at different points dependent upon the sizes of the checks.

5. In a check controlled apparatus, a support, a gauging and operating assembly movably mounted on said support, said assembly including a check chute, a slide on said support by which such chute is carried, and stop means for stopping checks of various diameters at different points along the length of said chute, said stop means being pivotally mounted upon said chute and having arms extending into said chute to be in the path of checks passing through the chute whereby to stop the checks at various points therein, a carrying member for printing type pivotally mounted with relation to said slide to cooperate with a check in said chute, said pivotally mounted carrying member being engageable edgewise with a check in said chute and having its pivotal motion limited thereby, operable means for moving said assembly and said slide as a unit, and printing means rigidly connected to said pivotally mounted carrying member, the stopping of the pivotally mounted carrying member predetermineding the printing position and being dependent upon the diameter of the check in the chute.

6. In a check controlled apparatus, a controlling means comprising a check-receiving chute having an opening through one side thereof for the reception of check-stopping arms, arms extending through said opening to serve as check-stopping means and swingable in said opening to release said checks, said arms, when at rest, serving to stop checks of different diameters at different points in the course of their travel through the chute, a pivoted support for said arms to swingably support them in said opening, pivoted means swinging into said chute edgewise thereof and engaging a check held therein by said arms, the check serving as a positive stop for the swinging movement of the pivoted means, the extent of movement of the pivoted means being dependent upon the diameter of the check, said arms holding the check in said chute until released by reverse movement of the pivoted means, actuating means to cause the means entering the chute to engage a check therein edgewise and cause movement of the chute, said chute being longitudinally movable and being moved longitudinally upon continued actuation of said actuating means after limitation of the swinging movement of said pivoted means, and printing means connected with said pivoted means to print different amounts dependent upon the diameters of the checks.

7. In a check controlled apparatus, a controlling means comprising a check-receiving chute having an opening through one side thereof for the reception of check-stopping arms, arms extending through said opening to serve as check-stopping means and swingable in said opening to release said checks, said arms, when at rest, serving to stop checks of different diameters at different points in the course of their travel through the chute, a pivoted support for said arms to swingably support them in said opening, pivoted means swinging into said chute edgewise thereof and engaging a check held therein by said arms, the check serving as a positive stop for the swinging movement of the pivoted means, the extent of movement of the pivoted means being dependent upon the diameter of the check, said arms holding the check in said chute until

released by reverse movement of the pivoted means, actuating means to cause the means entering the chute to engage a check therein edge-wise and cause movement of the chute, said chute being longitudinally movable and being moved longitudinally upon continued actuation of said actuating means after limitation of the swinging movement of said pivoted means, printing means connected with said pivoted means to print different amounts, dependent upon the diameters 10

of the checks, actuating means for the arms to swing them about their pivot whereby to cause movement of the arms out of check-stopping position, thus to release the check and permit it to pass through the apparatus, and stopping means for the actuating means to stop same in its reverse movement intermediate the limits thereof whereby to insure discharge of said check from said chute.

CLARENCE F. COOKSON.
